UNITED STATES PATENT OFFICE.

FRANK PIETRUSIAK, OF ST. PAUL, MINNESOTA.

CORE-MAKING MACHINE.

Application filed May 20, 1927. Serial No. 192,844.

My invention relates to a molding machine particularly useful in foundries, but also adaptable for other lines of manufacture such as making cement blocks, bricks and the like. The main object of the invention is to provide a simple and highly efficient machine for making cores for foundry use. These and other objects will appear in the following description and as illustrated 10 in the accompanying drawing, in which:

Fig. 1 is a top or plan view of one form of my device which involves a hand operated tamping or pressure device.

Fig. 2 is a side elevation of Fig. 1.

Fig. 3 is an enlarged detail view of certain core supporting means for the cap cylinder of my device, about as on line 3—3 in Fig. 2.

Fig. 4 is a vertical sectional elevation of 20 my improved machine including air pressed tamping or packing means.

Fig. 5 is an enlarged sectional view of the air control valve about as on line 5—5 in Fig. 4.

Referring to the drawing by reference numerals, 10 designates an elevated horizontal table held in fixed spaced relation above a base platform 11 by suitable spacer rods 12, said latter base normally resting on corner 30 blocks 13 or other suitable spacing means engaging a supporting surface or floor 14.

15 is an upright cylindrical shell with one end resting on platform 11 and its upper end normally projecting above an aperture 35 in table 10. The upper part of said shell is designated 15^T (Figs. 2 and 4), and is spaced from the lower part 15 (in Fig. 4) by integral wall parts 15^X forming a circular row of openings 15^A. 16 is a cylindrical 40 molding receptacle having a removable cap 17, and is of a diameter to rest concentrically on the upper perimeter of shell 15^T (see Fig. 4).

18 is a collar fixed on table 10 concentric 45 about the upper and open end of the shell 15 and flush with the latter, said collar preferably being an integral part of said shell 15. 18^A are a number of circularly spaced apertures through said collar, each occupied 50 by a vertically slidable L-shaped guide member 19. These lugs are all normally projected upwardly above the top of shell 15 to retain the member 16 concentrically between them, by compression springs 20 about a rod 19^R fixed one to the lower end 55 of each guide 19 and extending downwardly

through a bracket 23 and suitably fixed as at 21 in a ring 22 loosely encircling shell 15.

In Fig. 2, I have illustrated the cylinder 15^T only mounted in elevated position relative to base 11 in a bracket 24 fixed to both the upper and lower tables 10 and 11. In this lever operated type of my device a piston 25 is reciprocable within the cylinder by a depending guided piston rod 26 having rack teeth 26^T engaged by a toothed sector 27 keyed on a shaft 28 in a bearing 29 mounted on stand 11, said shaft having a hand lever 30 keyed to one end. Moving the lever as to the left in Fig. 2, raises the piston 70 rod and piston in shell 15. In Fig. 4 which illustrates an air or hydraulic operation, the piston rod 26 extends upwardly from piston 25 and carries another piston 31 at its upper end and within shell part 15^T. 32 is a bumper on the lower end of rod 26 to contact with the bottom end of shell 15 and 33 is an upwardly directed central pin fixed to the threaded upper end of rod 26 above piston 31 and being pointed upwardly. 34 is an upper cylinder head in shell section 15. 35 is a valve shell and 36 a three-way rotary valve within it to admit air in a pipe 36 and direct it as through a pipe 37 to the lower cylinder chamber A or as through a 80 pipe 38 to the upper cylindrical chamber B. Suitable passage is provided in the valve so that when air pressure is used in one chamber the air in the other chamber will exhaust through a pipe 39 in the valve chamber. 90 The valve may be oscillated by a vertical shaft 40, suitably journaled and on the upper part of said shaft is fixed a control handle 41 easily accessible to an operator.

42 are a pair of vertical rods, one at each side of shell 15, each fixed at 43 to lower table 11 extending upwardly through table 10, and above said latter table having a spacer pipe 44. 45 is a segmental lever rest bored at its opposite ends for the rods 42, one of the latter serving as a fulcrum for a hand lever 46, resting on said segment and adapted to be swung to diametrical position on top of cap 17 of the molding shell 16, to prevent upward movement of the latter during the molding operation of my device, presently to be described.

In the use of my device, core sand is first filled into the upper end of cylinder 15^T flush with the top thereof, thus filling the space above piston 31 in Fig. 4, or on top of piston 25 as in Fig. 2, it being understood

of course, that the mold cap or shell 16-17 has not been placed in position. Then the said shell 16-17 is placed concentrically on top of the cylinder between lugs 19, and lever 46 is swung as from dotted to full line position (Fig. 1) diametrically across the cap 17 and in engagement therewith, the lever being swung into a notch of a block 47 to hold it rigid. Now the valve lever 41 is manipulated so that compressed air enters chamber A forcing the piston rod 26 upwardly and the core sand above piston 31, (Fig. 4), is forced upwardly into shell 16 and compressed therein, it being understood that shell 16 is somewhat shorter than cylinder 15^T, and the piston 31 moves only up to the top line of said cylinder, also that prong 33 is pressed upwardly to form a cavity in the compressed core sand. The same effect is produced in the form of my machine illustrated in Figs. 1 and 2, it being understood that lever 30 is swung outwardly causing rod 26 to be moved vertically and piston 25 compressed the core sand in shell 16 as just described for Fig. 4.

48 is a U-shaped reach rod having its upper ends secured to ring 22 and its lower end engaged by a foot lever 49, which is fulcrumed on a cross bar or shaft 50 in the lower part of the device. The free end of said lever 49 extends forwardly and carries a foot engaging pad 49^P, which the operator presses down after the core sand has been compressed as described. This downward pressure on lever 49, pulls down on ring 22 which pulls bars 19^R and lugs 19 downwardly against the pressure of springs 20, said lugs thereby being pulled below the upper line of the cylinder and the shell 16 may be released, it being understood that the pressure piston is first dropped back to original position. Then the cap 17 may be unscrewed and the complete core print pushed out of the shell.

45 In Figs. 3 and 4, I have shown a device for preventing the completed core print from dropping back into the cylinder from shell 16 when the operator causes rod 26 to be moved downwardly again after the above described pressure stroke. This device comprises a ring 51 guided in a circular groove in collar 18 and having an integral lever 52 for oscillating the ring. 53 are a number of circular spaced inwardly directed cam arms each pivoted at 53^P to the ring 51. Each cam is arch shaped and normally is slidable in a slot 54 near the upper edge of the cylinder 15, (as in Fig. 4). It is obvious that when the crank 52 is swung as from full to

dotted line position, the cams 53 are projected into the upper end of the cylinder 15^T, (Fig. 4), while the piston 31 is in its uppermost position, said piston having radial upwardly opening apertures 31^A, registering with the apertures 54 and into which notches 65 the said cams are projected. Thus when the piston 31 is lowered, the cam arms 53 prevent the pressed core in shell 16 from falling.

My device is particularly useful in making standard size core prints for coring the central apertures of cast steel car wheels, but it is obvious that the core prints which can be made may be of various diameters and of different shapes in horizontal section, (not shown), and when a complete bore is desired through the core, the plug 33 is simply provided in necessary length and diameter wanted.

55 in Fig. 4 is a sheet metal shield of circular shape resting on top of cylinder head 34 and formed with outwardly and downwardly directed slopes to catch the sand which may get below piston 31 and guide it outwardly to prevent it from accumulating on the said cylinder head or getting into the lower cylinder 15.

I claim:

A core making machine comprising an upright fixed cylinder member mounted in a suitable framework, a piston reciprocable in said cylinder and a piston rod extending downwardly from said piston, a molding cylinder adapted to be removably fixed concentrically on the upper end of said fixed cylinder, said fixed cylinder adapted to be filled with core sand on top of the piston when the latter is in lowered position, said molding cylinder being shorter than the distance from the lowest position of the piston to the top of the fixed cylinder, means for moving said piston upwardly to the top of said fixed cylinder to compress the core sand in the molding cylinder, and a core retaining device mounted at the upper end of the fixed cylinder comprising a series of circularly arranged inwardly directed and curved cam arms, an oscillatable ring about said cylinder, said cams fulcrumed on said ring, said upper end of the fixed cylinder provided with apertures slidably engaged each by one of said cam arms, means for oscillating said movable ring to move said cam arms inwardly to support the lower part of the sand core pressed into the molding cylinder.

In testimony whereof I affix my signature.

FRANK PIETRUSIAK.
